UNITED STATES PATENT OFFICE.

JOHN L. WALSH, OF CHICAGO, ILLINOIS, ASSIGNOR OF ONE-HALF TO THOMAS J. CONLEY, OF CHICAGO, ILLINOIS.

WRENCH.

1,169,749.

specification of Letters Patent. Patented Jan. 25, 1916.

Application filed May 3, 1915. Serial No. 25,392.

To all whom it may concern:

Be it known that I, JOHN L. WALSH, a citizen of the United States, and a resident of Chicago, Cook county, Illinois, have invented certain new and useful Improvements in Wrenches, of which the following is declared to be a full, clear, and exact description.

This invention relates to wrenches of that type having a fixed jaw formed on the end of a handle, and a movable jaw sliding on the handle and adapted to be locked thereto at various positions of adjustment thereon.

The object of this invention is to provide locking means whereby the movable jaw may be free to slide along the handle for the purpose of adjustment, and having a loosely fulcrumed locking member capable of being moved into frictional contact with the movable jaw and handle in such manner as to bind the parts together.

The invention consists of certain novel features hereinafter fully set forth and claimed.

The invention is clearly illustrated in the drawing accompanying this specification, in which:

Figure 1 is a side elevation of a complete wrench embodying a simple form of the present invention; Fig. 2 is an enlarged, detail view of a fragment of the handle, the movable jaw and locking member, the movable jaw being shown in vertical, longitudinal section, and the locking member being shown in unlocked position; Fig. 3 is a view similar to Fig. 2, except that the locking member is shown in locked position; Fig. 4 is a vertical cross section taken on the line 4—4 of Fig. 1; and Fig. 5 is an enlarged, vertical cross section taken on the line 5—5 of Fig. 3.

Referring to said drawing, 10, designates the handle of the wrench, said handle having at one end the usual fixed jaw, 11, as is common in wrenches of this class. The movable jaw, 12, is slidably mounted on the handle, 10, and has a gripping face, 13, which opposes the gripping face, 14, of the fixed jaw. The part, 15, of the movable jaw has an opening, 16, therein, which is slightly longer than the width of the handle, 10, and in the lower edge portion, 17, of the movable jaw is threaded a screw, 18, the inner end of which projects into the hollow 55 of the part, 15. The adjacent edge of the

handle, 10, is formed with a centrally located, lengthwise extending groove, 19, slightly narrower in width than the diameter of the screw, 18, which screw has a rounded end that engages with the marginal edges of said groove, said contact being made when the movable jaw is clamped to the handle.

A recess, 20, is formed in the rear edge of the movable jaw, 12, and in said recess is a locking member, 21, which is loosely fulcrumed upon a pin, 22, secured in the side walls of the movable jaw. The locking member comprises a head, 23, and a handle, 24, the head having a slot, 25, formed therein, through which the pin, 22, extends, so that although the locking member is fulcrumed upon the pin, it is free to move bodily with respect thereto. When the locking member is in its locking position, the slot extends at right angles or approximately at right angles, to the handle. The head, 23, is somewhat oval shape in formation, and the rounded ends, 26, 27, thereof, are capable of being forced into gripping engagement with the end face, 28, of the recess, 20, and with the edge, 29, of the handle. It is to be observed that by reason of the elongated slot, the pin, 22, does not receive any strain occasioned in locking the movable jaw to the handle, but that the entire clamping action takes place between the ends of the head, 23, and the end wall, 28, of the movable jaw and edge, 29, of the handle.

In operation the locking member is swung into the position seen in Fig. 2, so as not to bind against the movable jaw or handle, and the movable jaw is adjusted against the nut or object which it is desired to grip with the wrench, and thereupon the handle or finger piece of the locking member is swung down toward the wrench handle, bringing the ends, 26, 27, of the head, 23, firmly into frictional engagement with the end wall, 28, and edge, 29, also raising the movable jaw and bringing the rounded end of the screw, 18, into frictional engagement with the marginal edges of the slot, 19, thus locking the movable jaw in position upon the handle. The screw, 18, may be adjusted, as occasion requires, to a position where it will bite into the edges of the groove, 19, and thereby aid the locking member in fixedly securing the movable jaw upon the

handle. Preferably, the length of the head, 23, is such that when in locked position, it stands at a slight angle to a line perpendicular to the handle and inclines toward the 5 fixed head, so that backward pressure upon the movable jaw tends to straighten or move the locking member into vertical position, whereby the grip becomes tighter as the pressure against the face, 13, of the movable 10 jaw, increases.

More or less variation of the exact details of construction is possible without departing from the spirit of this invention, and I desire, therefore, not to limit myself to 15 the exact form of construction shown and described, but intend in the following claims to point out all of the invention disclosed herein.

I claim as new and desire to secure by 20 Letters Patent:

1. A wrench comprising a handle having smooth edge portions and having a fixed jaw on one end, a movable jaw having a part 25 surrounding said handle and slidably mounted thereon, a locking member fulcrumed on said movable jaw and having oppositely disposed gripping edges adapted to engage with oppositely disposed portions of the movable jaw and handle, said locking 30 member having a pin and slot connection with the movable jaw, whereby the locking member may be swung into locking position with the pin out of engagement with either end of said slot.

2. A wrench comprising a handle having a fixed jaw at one end, a movable jaw having a portion surrounding said handle and slidably mounted thereon, said jaw having a re-

cess formed therein, a pin secured in said movable jaw and extending transversely 40 through said recess, a loosely fulcrumed locking member having an elongated slot for the reception of said pin and having two oppositely disposed, curved, bearing edges 45 capable of frictionally engaging an edge of the handle and an oppositely disposed face on the movable jaw.

3. A wrench comprising a handle having a fixed jaw at one end, and a movable jaw, 50 slidably mounted on said handle, said handle having a longitudinally extending groove in one edge, said movable jaw having a projection of slightly larger diameter than said groove and arranged to engage with the edges thereof when the movable jaw is in 55 locked position, and a locking member loosely fulcrumed upon said movable jaw and having oppositely disposed, curved, bearing faces adapted to engage with oppositely disposed faces of the movable jaw and 60 handle.

4. A wrench comprising a handle having a fixed jaw at one end, and a movable jaw, 65 slidably mounted on said handle, said handle having a longitudinally extending groove in one edge, said movable jaw having a screw, threaded therein, said screw being of slightly larger diameter than said groove and arranged to engage with the edges thereof when the movable jaw is in locked 70 position, and a locking member loosely fulcrumed upon said movable jaw and having oppositely disposed, curved, bearing faces adapted to engage with oppositely disposed faces of the movable jaw and handle.

JOHN L. WALSH.
